Attorney.

UNITED STATES PATENT OFFICE.

GIFFORD E. BLAYLOCK, OF BALTIMORE, MARYLAND.

TIRE-VALVE DEFULATOR.

1,288,815.

Specification of Letters Patent.

Patented Dec. 24, 1918.

Application filed June 29, 1918. Serial No. 242,565.

To all whom it may concern:

Be it known that I, GIFFORD E. BLAYLOCK, a citizen of the United States, residing at Baltimore city, State of Maryland, have invented certain new and useful Improvements in Tire-Valve Deflators, of which the following is a specification.

This invention relates to devices applicable to tire valves for the purpose of holding the valve open so that the inner tube of the tire may be completely deflated without removal of the valve "inside" from the valve stem, as is the usual practice.

The invention has for its object to provide a simple and efficient device of the kind stated, and also one which enables the tire tube to be inflated without removal of the device therefrom.

A further object of the invention is to provide a tire valve appliance of the kind stated by which the valve "inside" may be screwed into or screwed out of the valve stem.

Other objects and advantages of the invention will be pointed out in the detailed description appearing hereinafter, it being understood that, while the preferred embodiment has been disclosed, various changes and modifications may be made without a departure from the spirit and scope of the invention.

In order that the invention may be better understood, reference is had to the accompanying drawing forming a part of this specification.

In the drawing:

Figure 1 is an elevation of the device in place and ready for use, with parts of the valve stem to which it is applied broken away;

Fig. 2 is a vertical section of the device, and

Figs. 3 and 4 are side elevations of the device taken from opposite sides.

Referring specifically to the drawing, 10, denotes a fragment of the valve stem of the inner tube (not shown) of a pneumatic tire. The valve "inside" is shown at 11, it being provided with the usual lug 12 at its outer end to facilitate the operation of screwing the same into or out of the stem. These parts are of standard design which is well known, and hence a further description thereof is not necessary.

The supporting member of the device which is the subject matter of the present

application for patent comprises two opposite side legs 13 having a transverse connecting portion 14 at one end, with their opposite free ends inturned, as shown at 15, said inturned ends having apertures 16. The supporting member is a single piece of thin spring metal, and the legs 13 have a normal tendency to spread. It will therefore be evident that when the legs are sprung inward to overlap the parts 15 and to bring the apertures 16 into registration, the device may be slipped over the valve stem 10, and when released, the tendency of the legs to spread, causes the apertured portion of the parts 15 to securely grip the valve stem on the outside, whereby the device is securely held in place on said stem. The device is made of a thin strip of spring metal, so that the edges of the apertures 16 enter the thread grooves of the valve stem, whereby slipping of the device on said stem is effectually prevented.

The outer connecting portion 14 of the supporting device carries a swiveled wrench member for unscrewing the valve "inside" 11 to remove the same from the stem 10, and also for replacing the same. This wrench member comprises a tubular stem 17 having a head 18 at its outer end which defines a shoulder 19 seating on the outer surface of the part 14. The stem 17 passes loosely through an aperture in the part 14, and beneath the latter it has a collar 20 which cooperates with the shoulder 19 to hold the stem against longitudinal movement, it however being free to turn. The under side of the part 14 has a reinforcement 21 against which the collar 20 bears, and the collar is provided with a gasket 22 adapted to seat on the outer end of the valve stem 10 as shown in Fig. 2. The end of the stem 17 which is to engage the valve "inside" 11 has a kerf 11^a to seat the lug 12, so that when the stem is turned, the valve "inside" can be screwed in or unscrewed.

The central longitudinal bore of the stem 17 is threaded to receive a valve-unseating screw stem 23 of such length that it can be projected from the inner end of the stem 17 to engage the usual stem 24 extending from the valve proper, and hold the valve unseated. The outer end of the screw stem 23 has a head 25 for facilitating its manipulation.

In use, the supporting member hereinbefore described is slipped over the valve stem 10 and adjusted thereon to bring the gasket

22 seating on the outer end of the valve stem 10 as shown in Fig. 2. If it is now desired to open the valve and hold it open to let all the air out of the tube, it is necessary only 5 to advance the screw stem 23 until it pushes the stem 24 inward until the valve is unseated, and by reason of the fixed position of the supporting member on the valve stem 10, the valve will be thus held open.

10 To remove, or adjust the valve "inside" 11, the screw stem 23 is retracted, and the device is adjusted to seat the kerf 11^a over the lug 12, so that when the stem 17 is turned the valve "inside" will be screwed in 15 or unscrewed according to the direction the stem 17 is turned.

The device is designed more particularly for use in tire repair establishments. When repairing inner tubes, it is necessary to completely deflate the same, this being usually 20 done by removing the valve "inside" 11 from the stem 10. Hence, when the repair job is finished and the tube is to be tested by inflating the same, the valve "inside" must 25 be replaced. As some repairs necessitate several tests, much time is spent in removing and replacing the valve "inside," and furthermore, some styles of valve "insides" are destroyed upon removal from the valve stem. 30 These difficulties are entirely overcome by the use of the device hereinbefore described. The valve can be held open until the tube is completely deflated, and when the tube is to be inflated, it is necessary only to back 35 the stem 23 to release the valve. It is also not necessary to remove the device from the valve stem 10 when the tube is to be inflated. It will be noted that the stem 23 has a central longitudinal air passageway 26, so that 40 the air hose can be applied to the head 25 to let air into the tube.

One of the legs 13 has an inscription shown at 27 in Fig. 4 to identify the tire tube to which the particular device may be 45 applied. The customer receives a check or other token having an inscription corresponding to the inscription on the device which was applied to his tube. By this

means the jobs are easily identified and the customer is assured of having his tube returned to him. One of the legs 13 may also be provided with lips 28 to hold a check or tag 29 on which the customer's name appears, the date, the cost of the job, or any other desired data. 50

It will be noted that the stem 23 is not of uniform diameter throughout its entire length, its headed end being of greater diameter than the inner end which engages the valve stem 24. This is for the purpose 60 of obtaining enough metal for the air passageway 26, the same opening through the sides of the larger portion of the stem at the inner end thereof. The bore 27 in which the larger portion of the stem 23 works is 65 reduced at the inner portion of the member 17, as shown at 28' to seat the reduced portion of said stem, with sufficient space in said portion of the bore to allow the air to pass through the same from the larger portion of the bore. 70

I claim:

1. A tire valve appliance, comprising a supporting member, a swiveled wrench member carried by said supporting member, 75 and a longitudinally movable valve-unseating member carried by the wrench member.

2. A tire valve appliance, comprising a supporting member, a swiveled wrench member carried by the supporting member, 80 and a longitudinally movable valve-unseating member carried by the wrench member and having a longitudinal air passageway.

3. A tire valve appliance, comprising a supporting member, a swiveled wrench 85 member carried by the supporting member and having a longitudinal screw-threaded opening, and a valve-unseating screw stem in said opening.

In testimony whereof I affix my signature 90 in the presence of two witnesses.

GIFFORD E. BLAYLOCK.
